US0D1081611S

(12) **United States Design Patent** (10) **Patent No.:** **US D1,081,611 S**
(45) **Date of Patent:** **** Jul. 1, 2025**

(54) **TURNTABLE**

(71) Applicant: **AlphaTheta Corporation**, Yokohama (JP)

(72) Inventor: **Muneki Sugita**, Yokohama (JP)

(73) Assignee: **ALPHATHETA CORPORATION**, Yokohama (JP)

(**) Term: **15 Years**

(21) Appl. No.: **29/918,459**

(22) Filed: **Nov. 28, 2023**

(30) **Foreign Application Priority Data**

May 31, 2023 (JP) ..... 2023011075 D

(51) **LOC (15) Cl.** **14-01**

(52) **U.S. Cl.**

USPC **D14/203; D14/199**

(58) **Field of Classification Search**

USPC D14/160, 161, 162, 163, 167, 168, 169, D14/175, 199, 200, 201, 202, 203, 261, D14/262, 263, 264, 474, 478, 498, 499, D14/500, 501, 502, 503, 504, 505, 506, D14/507, 509, 510, 129, 131, 208, 173

CPC G11B 23/00; G11B 19/16; G11B 19/2009; G11B 17/16; G11B 17/02; G11B 17/04; G11B 33/02

(57) **CLAIM**

The ornamental design for a turntable, as shown and described.

DESCRIPTION

FIG. 1 is a top-right-front perspective view showing the turntable of the design;

FIG. 2 is a bottom-left-rear perspective view thereof;

FIG. 3 is a front view thereof;

FIG. 4 is a rear view thereof;

FIG. 5 is a left-side view thereof;

FIG. 6 is a right-side view thereof;

FIG. 7 is top view thereof;

FIG. 8 is bottom view thereof; and,

FIG. 9 is a top-right-front side perspective view of the turntable shown in an alternate configuration with the transparent member removed.

The oblique line shading in the drawings depicts transparent surfaces of the turntable of the design.

1 Claim, 9 Drawing Sheets
